UNITED STATES PATENT OFFICE.

BERNARD RUSSEL DIETZ, OF CANTERBURY, ENGLAND.

MILITARY SIGNALING APPARATUS.

1,135,778.

Specification of Letters Patent.

Patented Apr. 13, 1915.

Original application filed April 17, 1908, Serial No. 427,743. Divided and this application filed December 28, 1908. Serial No. 469,618.

To all whom it may concern:

Be it known that I, BERNARD RUSSEL DIETZ, a subject of the King of Great Britain, residing at St. Nons, Canterbury, in the county of Kent, England, have invented certain new and useful Improved Military Signaling Apparatus, of which the following is a specification.

This invention relates to improvements in the apparatus described in my copending application Serial No. 427,743, of which this is a division, and has for its object to adapt the same for use in indicating positions or the whereabouts of parties in connection with military and other operations in the dark or at night; the object being to render the positions observable by, say, the officer commanding, but to prevent the same being ascertained by the opposing force or parties.

20 The apparatus is also serviceable as a means of signaling or communicating.

According to my invention it is desirable to have an illuminating device which the officer may conveniently carry and by means of a glow lamp, or other illuminating means such as a slow match, tinder or the like indicate to his men and similarly his general or commanding officer their position or whereabouts while concealing the same from the enemy. At the same time the device may serve in leading the men. For this purpose the apparatus may comprise a disk or disk like device adapted for being fitted into a suitable holder and formed or provided with a receptacle for an illuminant such as above referred to or which may comprise a lamp of the acetylene or other type and of a portable character.

In order that the said invention may be clearly understood and readily carried into effect, I will proceed to describe the same with reference to the accompanying drawing, in which:

Figure 1 being a vertical section of the device. Fig. 2 a view also in section of a portion of the device drawn to a larger scale. Fig. 3 is a view in section illustrating an alternative mode of effecting the raising of the wick, slow match or tinder. Fig. 4 is a front elevation of the device. Fig. 5 is a side elevation of the form of the device shown in Fig. 4; and Fig. 6 is a view in elevation of the form of the device illustrated in Fig. 4 and showing more clearly the means whereby the light is obscured.

Referring to the form of apparatus illustrated in Figs. 1, 2 and 3, *a* is a disk which may be black. In the center of the disk or in any other suitable situation thereon, is mounted a casing *e* in which is disposed a reflector *f* and a glass *g*. The glass may be clear or of red or other color as may be desired. A wick tube *h* or other illuminating means projects into the interior of the casing *e*, the wick *i* being passed through the tube *h* and into a tubular receptacle *k* adapted for being used as a handle or for being secured to the disk device, an attaching means of any suitable or appropriate form being employed for effecting the necessary connection of the parts. The wick *i* may be raised by means of star wheels *i'* *i''* operated by a milled turning head *i²* situated upon a spindle carried laterally through the casing *k*; or the star wheels *i'* *i''* may be actuated by a milled head *i²* mounted on a spindle *i³* arranged parallel with the casing *k* and provided with a worm *i⁴* for operating the gear wheels *i⁵* *i⁶* pertaining to the star wheels *i'* *i''* (Fig. 4). The end of the handle or casing *k* remote from the disk *a* may be closed by a cap *k'* which may be secured to the casing *k* by a bayonet slot or other fastening. By means of the milled turning head *i²*, the raising of the wick may be readily accomplished while the apparatus is held in one hand.

The arrangement illustrated in Fig. 5 comprises a circular frame *a* having a filling *a'* constituting a disk. The front of the disk is furnished with a segment *b* hinged to the main portion *a* at *b'* *b''* or along the line of junction with the said main portion *a*. The disk *a*, *b* is mounted on a handle or support *c* which may be as shown of tubular form or the handle may be telescopic as will be readily understood. The spindle *b'* may be bent at *b''* to allow the casing *e* and lens to be placed in the center of the disk. The bent portion *b''* may be provided with a piece of pliable material, such as chamois leather, which would accommodate itself as the movable part of the disk is operated backward and forward for signaling purposes; the aforesaid pliable material being adapted to cover the light. The match or wick *i* may be coiled in the handle *c* as before described. The spindle *b'* may terminate in a part *d* and an actuating piece *d'*. The hinged segment *b* is operated by means

of the spindle d and finger piece d' so as to expose and obscure the light.

It will be obvious that the herein described apparatus may be used in communicating or signaling somewhat after the manner of the flags ordinarily employed or the said apparatus may be adapted to a code.

What I claim and desire to secure by Letters Patent of the United States is:—

1. A portable signaling apparatus comprising an opaque disk-like device, a handle secured to and projecting from the periphery of the disk and in the plane of the same, a light giving device fitted centrally in one face of the said disk, a pivotally mounted segment on the same face of the disk, and means carried by the said handle for turning the said segment on its pivot to expose and obscure said light giving device.

2. In a portable light signaling apparatus, the combination of an imperforate disk,

a source of light arranged centrally of said disk, a diametrically arranged spindle rotatably mounted on said disk on the side 25 thereof adjacent the source of light, a segment arranged on said spindle and corresponding in dimensions to one half of the imperforate disk, a central loop on said spindle extending over the source of light, a 30 flexible pocket secured to said loop and to the imperforate disk on one side of said spindle, a finger piece on said spindle for turning the segment so that the flexible pocket may cover the source of light, and a handle secured to the said device and projecting from the same in the plane thereof.

In testimony whereof I affix my signature in presence of two witnesses.

BERNARD RUSSEL DIETZ.
